UNITED STATES PATENT OFFICE.

GOTTLIEB H. HOELSCHER, OF HAWARDEN, IOWA, ASSIGNOR OF ONE-FOURTH TO A. D. HORTON AND ONE-FOURTH TO JOHN SMITH, BOTH OF HAWARDEN, IOWA.

RAILWAY-RAIL JOINT.

1,087,016.

Specification of Letters Patent. Patented Feb. 10, 1914.

Application filed May 14, 1913. Serial No. 767,671.

To all whom it may concern:

Be it known that I, GOTTLIEB H. HOELSCHER, a citizen of the United States, residing at Hawarden, in the county of Sioux, State of Iowa, have invented certain new and useful Improvements in Railway-Rail Joints; and I do hereby declare the following to be a full, clear, and exact description of the invention, such as will enable others skilled in the art to which it appertains to make and use the same.

This invention relates to railway rail joints, and it more particularly relates to an improved form of boltless railway joint.

15 An object of the invention is to provide railway rails each having enlarged ends, one of which is provided with a socket and the other with a tenon adapted to fit in the socket of the contiguous rail end.

20 Another object of the invention is to provide a railway joint of this character which is of such configuration and proportions as to provide a combined railway joint and chair.

25 Another object is to provide a railway joint of this character in which the rail heads or tread sections are intermeshed, so as to prevent the jarring and battering by the rolling stock, that takes place at the ends 30 of ordinarily constructed rails.

Another object of the invention is to provide a railway joint of this character in which proper allowance is made for expansion and contraction of the rails.

35 Another object is to provide for quickly uniting the rail ends.

Another object is to provide a joint of this character which can only be disconnected, when the railway track is completed, by 40 sawing or otherwise severing one of the rails, or by disconnecting and moving a considerable number of rails; thereby effectually preventing train wreckers from accomplishing their work by disconnecting the 45 rail joints.

Another object of the invention is to provide a rail joint of this character which is exceedingly strong, compact, comparatively inexpensive and thoroughly efficient.

Other objects and advantages may be recited hereinafter and in the claims.

In the accompanying drawings, which supplement this specification: Figure 1 is a perspective view, illustrating the adjacent ends in position to be moved into locking 55 position. Fig. 2 is a horizontal sectional view taken on the line 2—2 of Fig. 1. Fig. 3 is a perspective view, similar to Fig. 1, of a modified form of my improved rail joint, and Fig. 4 is a horizontal sectional 60 view taken on the line 4—4 of Fig. 3.

Referring to these drawings, in which similar reference characters correspond with similar parts, throughout the several views: The enlarged rail ends 5 and 6 are similar 65 in contour, except that the end portion 5 is provided with the locking lug 7, while the end portion 6 is provided with a recess 8 into which the lug 7 is adapted to be seated. Each portion 5 and 6 has inclined lateral 70 sides 9, the planes of which converge toward a line above the center of the rail tread 10 and extend in the longitudinal direction thereof, and preferably being integral therewith. One end of the rail tread in provided 75 with a tongue or tenon 11, which extends from the aperture 8 to the top of the rail tread, and is flush therewith, while the other end of the tread 10 is provided with a vertical groove or mortise 12 into which the 80 tenon 11 is adapted to be seated and snugly fitted. This groove extends from the top 13 of the locking lug 7 to the top of the rail tread. This top surface 13 is parallel with the bottom surface 14, both of these plane 85 surfaces being on planes parallel with the top of the rail tread and the bottom 15 or chair element of the rail.

The locking lug is provided with a lateral extension or shoulder 16, and between this 90 shoulder and the shoulder 17 is a groove 18, into which the shoulder 19 is adapted to be seated. A groove 20 is provided between the shoulder 19 and the inner rear wall of the recess or cavity 8.

The bottom 21 and top 22 of the cavity 8 are horizontal and parallel, and are spaced apart a distance equal to the vertical dis-

tance between the surfaces 13 and 14, so that these surfaces will fit snugly between the surfaces 22 and 21 respectively.

The horizontal width of the shoulders 16 5 and 19 respectively is less than the horizontal width of the grooves 18 and 20 respectively, so that after the rails have been securely locked together in their normal alined position, the rails are susceptible of 10 sufficient longitudinal movement to compensate for expansion and contraction thereof. The surface 7^a of the lug 7 is convexed while the contiguous inner surface of the cavity 8 is concaved; and so, when the lug 7 has been 15 started into the cavity 8, the convexed surface slides easily and unobstructedly along the concaved wall, thereby greatly facilitating the locking of the rail joints.

Obviously, when the rails have been 20 locked together, it is impossible to separate them without relative movement thereof, so as to place them in angular relation to each other, and it is also obvious that the rails must be started into locking engagement, 25 when placing them together, by first placing them in angular relation, as illustrated in the drawings.

The relatively broad and solid bottom 21 constitutes a solid foundation on which the 30 locking lug 7 rests, so as to prevent vertical movement of the rail ends relative to each other, and therefore, it will be seen that this arrangement substantially constitutes a rail chair as well as a secure locking 35 joint.

In lieu of the form of rail joint described in the foregoing, I may provide a somewhat similar though somewhat modified form of the invention in which I employ two locking 40 lugs 7' and 7^a respectively, the former being the lower, and the latter being the upper. These locking lugs are provided with lateral extensions 16' and 16^a respectively, while notches or grooves 18' and 18^a correspond with the groove 18, previously described. The shoulders 19' and 19^a engage 45 with the elements 16^a and 16' respectively, and are fitted within the grooves 18^a and 18' respectively. The locking lug 7^a fits snugly 50 between the upper surface of the lug 7' and the upper surface of the cavity above the lug 7', while lug 7' fits snugly within the cavity below the lug 7^a, sufficient space being allowed within the cavities and the 55 grooves for allowing for the expansion and contraction of the rails.

The locking lugs 7' and 7^a are evenly curved or convexed at 7^b and 7^c respectively, while the contiguous walls of the respective 60 cavities are concaved; so that when the joints are being fitted together the said convexed surfaces slide upon the respective concaved surfaces, and thereby facilitate

the ease and convenience in connecting the rails.

From the foregoing, it will be seen that I have provided a rail joint of this character which is fully capable of attaining the objects and advantages recited in the foregoing.

I do not limit my invention to the exact details of construction, combination and arrangement of parts, as herewith illustrated and described, but my invention may only be limited by a reasonable interpretation of 75 the claims.

I claim:

1. A railway rail joint consisting of rail sections each having its ends enlarged, one of the enlarged ends being provided with a cavity having a shoulder and a tenon and a concaved wall therein, the other rail end being provided with a locking lug having a shoulder and a groove and a convexed surface, said locking lug of one rail section being adapted to be fitted into the cavity of the other rail section by placing the rail sections at an angle to each other and imparting such relative movement thereto as to cause said convexed surface to slide upon 90 said concaved wall and to move the respective shoulders and grooves into locking engagement.

2. In a railway rail joint, a rail section having an enlarged end with a cavity formed 95 therein and provided with a shoulder and a concaved and substantially vertical wall within the cavity, said enlarged end being provided with a vertical tenon extending from the cavity to the top of the rail tread, 100 a second rail section provided with an enlarged end having a locking lug which is provided with a substantially vertical convexed surface and having a shoulder formed thereon, said second rail section having a 105 mortise extending from the locking lug to the top of the rail tread, whereby the rail sections may be locked together by placing them at an angle to one another and inserting said locking lug in said cavity by so 110 moving the rail sections relative to each other as to cause the convexed surface to slide upon the concaved surface and thereby seat said tenon within said mortise while moving said shoulders into interlocking position.

3. A railway rail joint comprising two rail sections each having an enlarged end, each said enlarged end being provided with a locking lug and a cavity adjacent thereto, 120 each locking lug being provided with a shoulder, each enlarged end being provided with a shoulder within its cavity thereof, each locking lug being provided with a convexed surface, each enlarged end being provided with a concaved surface within its 125

cavity, so that the rail sections may be locked together by placing them in angular relation with each other and imparting such relative movement thereto as to cause one of said locking lugs to slide upon the other said locking lug, and move said locking lugs into the respective cavities with their respective convexed surfaces sliding upon the concaved surfaces, so that the shoulders

within the cavities are engaged by the shoulders of the respective locking lugs.

In testimony whereof, I affix my signature, in the presence of two witnesses.

GOTTLIEB H. HOELSCHER.
